CUE TRIMMING MACHINE.
FILED SEPT. 8, 1921.

2 SHEETS-SHEET 2

UNITED STATES PATENT OFFICE.

WILLIAM J. F. BOETTCHER, OF CHICAGO, ILLINOIS.

CUE-TRIMMING MACHINE.

Application filed September 8, 1921. Serial No. 499,163.

To all whom it may concern:

Be it known that I, WILLIAM J. F. BOETTCHER, a citizen of the United States, residing at Chicago, in the county of Cook 5 and State of Illinois, have invented new and useful Improvements in Cue-Trimming Machines, of which the following is a specification.

The present invention has reference to 10 cutting machines and particularly to machines adapted for cutting and trimming cue ends and tips.

One object of the invention is to provide 15 a machine of this character by means of which the end of a cue can be completely cut off, tenoned, or the tip trimmed to the desired size and shape.

Another object is to provide a device of 20 this character by means of which the depth of the cut for cutting off the tip to a diameter equal to that of the cue end is attained, with the result that the tip will form a perfect and smooth continuation of the body of the cue.

Another object is to provide a device of 25 this character whereby the cue may be supported in different positions so that the cue tip can be cut on an angle to produce a flaring continuation of the body.

Another object is to provide a device of 30 this character by means of which the cue can be easily and accurately fed toward the cutter, as the cutting proceeds.

A further object is to provide a device of 35 this character which having once been set to cut a tenon of a certain diameter, no further adjustments are necessary, no matter what the original diameter of the cue end may be.

A still further object is to provide a device of 40 this character which will cut off the end of the cue and trim the fiber without requiring original adjustment.

Other objects and advantages will be apparent from the following description when 45 taken in connection with the accompanying drawings.

In the drawings:

Figure 1 is a top plan view of the machine;

Figure 2 is a side elevation of the same.

Figure 3 is a vertical transverse section on the line 3-3 of Figure 2.

Figure 4 is an enlarged vertical longitudinal sectional view on the line 4-4 of 55 Figure 1.

Figure 5 is a vertical transverse section on the line 5-5 of Figure 2.

Figure 6 is a slightly enlarged elevation of the cutter and cue end, showing the stop 60 or gage for regulating the depth of the cut into the cue tip.

Referring particularly to the accompanying drawings, 10 represents a casing which has a screw clamp 11 for attaching the same 65 to the edge of a table. In this casing are supported the shafts 12 and 13, the former carrying a large gear 14, while the other shaft carries a smaller gear 14^a, said smaller gear being in mesh with the larger gear and 70 being driven thereby. On the outer end of the shaft 12 is mounted a crank handle 15, by means of which the gears are rotated. The other shaft 13 extends a short distance 75 beyond the other side of the casing and through a bearing sleeve 13^a, and has on its outer end the rotating cutter 16. In the outer end of the cutter there is formed a socket 16', in which is received the stem 17 of the cutter stop or guide 18. It will 80 be noted that the diameter of the stop 18 is equal to the diameter of the cutter, that is the outer peripheral face of the stop lies in the same plane as that of the outer faces of the spiral cutting ribs of the cutter. 85

This arrangement prevents the cutter from cutting the end of the cue, or the cue tip, deeper than the external surface of the body of the cue.

Supported on the bearing sleeve 13^a is a 90 block 19, and extending outwardly from the block, and in a direction away from the cutter, is a rod 20. On the other end of the rod 20 is carried a stem 21 which is adapted to rest on a table or bench, and 95 carried on its upper end an adjustable fork 22 for supporting the butt end of the cue, said fork being adjustable laterally. Formed on the block 19 are the eyes 23 through which slides a transverse oppositely threaded shaft or rod 24, and threadedly supported on this rod are the jaws 25 of a vise, and between which jaws the tip portion of the cue is held while being acted upon by the cutter. The block 19 has the threaded sockets 27 in which are secured the threaded rods 26 and 28. On the outer ends of the rods 26 and 28 are engaged the nuts 29 and 30, the former being a single nut 100 while the latter represents a pair, one of 110 which 30' being a jam nut. The rod 24 is positioned lengthwise between the nuts 29

and 30 and it is adapted to be moved in the direction of its length by turning the nut 29 so that it bears against one end of the rod and pushes said rod forwardly. 5 The nut 30 operates as a stop to limit this movement of the rod when the rear end of the latter strikes said nut. As the rod carries the cue-holding jaws 25, the cue is fed to the cutter 16 by advancing the rod 24 as 10 described.

Carried by the block 19, and projecting therefrom in parallel relation to the cutter, is a stop bar 31, against which the tip end 15 of the cue is engaged to regulate the length of the cut thereon by the cutter. The block 19 is removably mounted on the sleeve 13^a, and it is also adjustable thereon in the direction of its length. The block is secured in adjusted position by a set screw 33 carried thereby and engageable with the sleeve. 20 As the block 19 carries the supporting rod 24 of the cue-holding jaws 25, and said block is adjustable along the sleeve 13^a in a direction parallel to the axis of the cutter 16, the 25 jaws can be correspondingly adjusted to properly position the work to the cutter to obtain a cut of the desired length.

When a cue end is to be cut off, the stop member 18 is removed, and upon turning the 30 handle, the cutter will be rotated. The operator turns the nut 29 which bears against the adjacent end of the rod 24, with the result that the rod 24 is advanced until the other end of said rod abuts against the adjacent nut 30. It will be noted that the rod 24 slides through the guide eyes 23, and when the rod has come into contact with the nut 30, the cutter has removed the desired amount of material from the cue end, or 40 the tip thereof. It will be understood of course, that during the operation of the cutter the cue must be rotated by the operator so that the cutter may operate all the way round the cue. The jaws 25 must be 45 adjusted to firmly hold the cue, but not so tight as to prevent the cue from being rotated as stated.

After cutting the tenon to the required size, a rawhide ferrule is placed on the tenon, 50 and it is necessary to turn this ferrule down to the exact diameter of the adjacent portion of the body of the cue. This is done in the same manner as when cutting the tenon, except that the jaws, and other parts are 55 adjusted to different positions, and the jaws and cue are fed toward the cutter through a shorter distance. By adjusting the fork of the butt end support toward one side or the other, the cue will be held at an angle with

respect to the cutter, and by this arrangement the cutter will cut the ferrule so that it will have an outwardly flaring end. 60

What is claimed is:

1. A cue trimming machine including a rotatable cutter, a block, a cutter shaft, 65 a clamp for a cue end slidably mounted on the block for movement toward and away from the cutter, adjusting means for the clamp slidable in the block, a feeding means for moving the clamp bodily, and a 70 stop means adjustable into different positions to limit the movement of the clamp.

2. A cue trimming machine including a support, intergeared shafts on the support, 75 a rotary cutter carried by one of the shafts, a bearing sleeve for the cutter shaft, a block removably supported on said sleeve, cue holding jaws adjustably carried by the block, and means on the block for limiting the movement of the jaws toward and away 80 from the cutter.

3. In a cue-trimming machine, a support, a rotary cutter carried by the support, a block carried by the support and adjustable in a direction parallel to the cutter axis, a 85 cue-holder carried by the block and positioned to locate the cue alongside the cutter, said cue-holder being also adjustable in a direction transverse of the cutter axis, and a stop carried by the block and positioned 90 for engagement by the cue-end, said stop being adjustable in a direction parallel to the cutter axis.

4. In a cue-trimming machine, a support, 95 a bearing sleeve projecting from the support, a shaft journaled in said bearing sleeve and projecting therefrom, a cutter carried by the projecting end of the shaft, cue-holding means positioned to locate the cue end alongside the cutter, and a support for the 100 cue-holding means carried by the bearing sleeve, said holding means being adjustable on the support in a direction transverse of the cutter axis.

5. In a cue-trimming machine, a support, 105 a bearing sleeve projecting from the support, a shaft journaled in said bearing sleeve and projecting therefrom, a cutter carried by the projecting end of the shaft, cue-holding means positioned to locate the cue-end 110 alongside the cutter, and a support for the cue-holding means carried by the bearing sleeve, and adjustable in the direction of the length of the sleeve, the cue-holding means being adjustable on the support in a direction transverse of the cutter axis.

In testimony whereof I affix my signature.

WILLIAM J. F. BOETTCHER.
